US0D1041900S

(12) United States Design Patent (10) Patent No.: US D1,041,900 S
(45) Date of Patent:  Sep. 17, 2024

(54) HANDLE FOR HANDBAGS

(71) Applicant: BOTTEGA VENETA S.R.L.,
Montebello Vicentino (IT)

(72) Inventor: Matthieu Blazy, Milan (IT)

(73) Assignee: Bottega Veneta S.R.L., Montebello
Vicentino (IT)

() Term: 15 Years

(21) Appl. No.: 35/517,313

(22) Filed: Apr. 21, 2023

(80) Hague Agreement Data

Int. Filing Date: Apr. 21, 2023

Int. Reg. No.: DM/228965

Int. Reg. Date: Apr. 21, 2023

Int. Reg. Pub. Date: May 26, 2023

(30) Foreign Application Priority Data

Oct. 31, 2022 (EM) 015001962-0020

(51) LOC (14) Cl. 03-01

(52) U.S. Cl.

USPC D3/318

(58) Field of Classification Search

USPC D3/232, 234, 239–246, 318, 328;
D8/303, 305, 316; D9/434, 443, 455

CPC A45F 5/102; A45F 5/1046; E05B 1/0015

See application file for complete search history.
